UNITED STATES PATENT OFFICE.

WILLIAM N. BRYERS, OF HELMER, MICHIGAN.

FLOATING-JACKET.

1,090,596.

Specification of Letters Patent. Patented Mar. 17, 1914.

Application filed January 11, 1913. Serial No. 741,454.

To all whom it may concern:

Be it known that I, WILLIAM N. BRYERS, a citizen of the United States, residing at Helmer, in the county of Luce and State of Michigan, have invented certain new and useful Improvements in Floating-Jackets, of which the following is a specification.

This invention relates to floating jackets adapted to be used by persons for the purpose of keeping them afloat, so that the device can be used as a part of a bathing suit, as well as a life-preserver, and it has for one of its objects the provision of an article of this character which comprises a jacket 15 having a buoyant air member secured thereto in such a manner that the freedom of movement of the arms will not be interfered with.

The invention has furthermore for its object the particular organization of the buoyant member on the jacket, so that the front and rear portions are substantially balanced in their efficiency to produce the best results.

25 Further objects of the invention will hereinafter appear and be particularly defined in the claim.

The invention has been clearly illustrated in the accompanying drawings in which—

0 Figure 1 represents a front view of the device as worn by a person. Fig. 2 is a side view thereof, Fig. 3 is a rear view, and Fig. 4 is a cross section of the inflated buoyant member and illustrates the method of attaching the same to the jacket.

Referring to the drawings, 10 denotes a jacket or blouse made from any suitable flexible material and shown herein as a part of a bathing suit. Disposed around the 40 body portion of the jacket is the buoyant member above referred to, comprising a tube 11 made of thin flexible rubber and having at the front thereof an extension 11' provided with an inflating nipple 12 which 45 may be of any desired or well known construction. The tube 11 is laid on the jacket in zig zag form having its upper and lower bends 11" well rounded as shown so as to prevent creases or kinks in the same, 50 so that the buoyant member may be inflated

from the extension 11' above referred to, throughout its entire length. The buoyant member is covered by a casing 13 made of canvas or other like material and stitched to the fabric of the jacket, as shown at 14. 55 This construction will facilitate the ready removal of the tube when desired, one end thereof terminating on one side of the breast portion while the extension 11' may be slipped beneath so as to be entirely out of 60 the way, when not in use. Both the front and rear portions of the jacket are thus provided with the zig zag layers of the tube, and they are in communication through side lengths 15 which may be made 65 separate from, or unitary with, the front and rear tube portions, and these side tubes are placed preferably at the waist-line so as to avoid their being damaged, as far as possible. 70

It should be understood that the casing or envelop is sufficiently roomy that the tube may be inflated as far as desired, and for that reason I do not confine myself to any particular shape or form herein shown. 75 Other changes may be made in the organization or combination of the buoyant member with the jacket without departing from the spirit of the invention.

I claim:—

The combination with a garment, of an inflatable air tube laid zig-zag on both the front and back portions of said garment and having both of its ends closely adjacent each other at the front portion of said garment, and having the connecting portions of its front and back sections disposed near the waist line of the said garment, a single device attached to one tube-end for inflating said tube throughout its length, and a 85 casing following and covering the entire tube and secured by its marginal edges to the garment.

In testimony whereof I affix my signature in presence of two witnesses.

WILLIAM N. BRYERS.
